UNITED STATES PATENT OFFICE.

ROGER W. ANDREWS, OF PITTSBURGH, PENNSYLVANIA, ASSIGNOR TO NORTHERN EQUIPMENT COMPANY, OF ERIE, PENNSYLVANIA, A CORPORATION OF PENNSYLVANIA.

BOILER FEED-WATER REGULATOR.

Original application filed June 7, 1918, Serial No. 238,765. Divided and this application filed August 25, 1921. Serial No. 495,323.

To all whom it may concern:

Be it known that I, ROGER W. ANDREWS, a citizen of the United States, residing at Pittsburgh, in the county of Allegheny and 5 State of Pennsylvania, have invented certain new and useful Improvements in Boiler Feed-Water Regulators, of which the following is a specification.

This invention relates to apparatus for 10 controlling the flow of water to boilers, and this application is a division of my copending application, Serial No. 238,765, filed June 7, 1918.

In the operation of steam boilers I have 15 found it desirable, in the use of feed-water regulators operating the feed-water valve of the boiler, to vary more or less, at times, the opening of the valve, independently of the regulator, and without interfering with 20 the normal operation of the regulator on the valve.

For instance, it has been found in practice, in feeding water to boilers, particularly 25 those of large capacity or comprising several drums, that the water level in different portions of the boiler, particularly in different drums, may vary very materially, due partly to irregular conditions of the fire which causes variations in the temperature 30 of the water. By the ordinary method of controlling the feed-water valve by a single regulator connected to one drum water will be fed into that drum without reference to the elevation of the water in the other drum. 35 One of the objects of this invention is to cause both drums to assist in the regulation of the feed-water valve, so that if the water in either becomes high or low the valve will be operated accordingly.

40 Of the accompanying drawings, Fig. 1 is an elevation of a boiler having three drums and two feed-water regulators operating the feed-water valve, which embodies the features of my invention; Fig. 2 is a sectional view of the feed-water valve and the immediate operating means along the line 2 of Fig. 1; Fig. 3 is a section along the line 3 of Figure 2; Fig. 4 is a section along the line 4-4 of Fig. 1.

45 Any suitable type of feed-water regulator may be used, yet, for the purpose of illustrating my invention, I prefer the type which is fully shown and described in the Patent No. 1,148,483 issued to me July 21,

1915. In this particular instance the regulators are shown at the same elevation, and 55 inclination and length; but it should be understood that unlike regulators may be used.

I prefer to mount the two regulator tubes 60 70 and 71 on the same base 72, tube 70 controlling lever 73 and tube 71 controlling lever 74, in a suitable manner. Tube 70 is connected by pipes 75 and 76 with the remote drum 77 of the boiler, and tube 71 is 65 connected, by means of pipes 78 and 79, with the adjacent drum 80 of the boiler. Both tubes are operatively connected in any suitable manner to the same feed-water valve 70 82 in the pipe 83 which delivers water to the lower portion of the drum 80.

The valve 82, which I prefer to use with 75 this system, comprises a plunger 84 which has a seat 85. These two members are mounted for relative and rotational longitudinal movement, and they have ports 86 and 87 which register when the two members are in a certain relative position; and as the cylinders are relatively rotated the opening through the registering ports are diminished 80 in size until, when rotated to the position shown in Fig. 3, the ports are entirely closed. Also relative longitudinal movement will vary the openings in the ordinary manner. 85

I prefer in this particular case to operatively connect the tubes 70 and 71 to the valve 82 in the following manner: Tube 71 is operatively connected to the stem 92 of plunger 84. This connection is made by 90 means of the lever 74 a rod 88 and a weighted lever 89 pivoted to the frame 93. It will be seen by this that, as the tube 71 expands, the plunger 84 will be given a longitudinal movement. And tube 72 is operatively connected to the same stem 92 by means of the lever 73 rod 90 and a weighted arm 91 fixed to the stem 92. By this arrangement, when the tube 72 expands the valve plunger will 95 be given a rotational movement, it being understood that the end 94 of the lever 89 is rotatably connected to the plunger stem 92. 100

As a consequence, whenever the water level in the remote drum 77 varies, it will have an effect on the feed-water valve in addition to 105 the normal effect of the ordinary feed-water regulator 71 which is controlled in the ordinary manner by the drum 80.

Although I have described with much particularity the specific feed-water regulator system which I prefer, yet I wish it understood that other types and forms of feed-water regulators may be used, and various other modifications in the system, may be made by those skilled in the art to produce substantially the same results without departing from the scope of my invention as disclosed by the following claims.

10 I claim as my invention:

1. The combination of a boiler, two feed-water regulators and a feed-water valve, said valve comprising a plunger and a seat therefor, said plunger and seat being relatively movable rotationally and longitudinally, the first of said feed-water regulators being operatively connected with said boiler and with said valve and arranged to move said plunger and seat relatively longitudinally, and the second of said feed-water regulators being operatively connected with said boiler at a portion of said boiler remote from the point of connection of said first regulator, 25 said second regulator being also operatively connected with said valve and adapted to move said plunger and seat relatively rotationally, said plunger and seat when in one relative position forming an opening through said valve, and said opening being varied as said plunger and seat are moved relatively either rotationally or longitudinally.
2. The combination of a boiler, a feed-

water valve for said boiler, said valve having a plunger, a feed-water regulator operatively connected with said boiler and with said valve and being arranged to move the valve plunger to vary the opening through said valve, and a second feed-water regulator operatively connected with said boiler at a point of said boiler remote from the point of connection of said first mentioned regulator, said second regulator being operatively connected with said valve and being arranged to vary the opening therethrough independently of said first mentioned feed-water regulator.

3. The combination of a boiler, having a plurality of drums, a feed-water valve for said boiler, said valve having a plunger and a seat therefor, a feed-water regulator operatively connected with one drum of said boiler and with said valve and arranged to vary the relative positions of the valve plunger and its seat in order to vary the opening through said valve, and a second feed-water regulator operatively connected with another drum of said boiler and with said valve and arranged to vary the relative positions of the plunger and seat independently of said first mentioned feed-water regulator.

In testimony whereof, I hereunto set my hand.

ROGER W. ANDREWS.
